CLAIM

The ornamental design for a storage bag, as shown and described.

DESCRIPTION

FIG. 1 is a perspective view of a storage bag, showing our new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof; and,

FIG. 8 is a partial enlarged view of FIG. 1.

The dash-dash broken lines depict portions of the storage bag that form no part of the claimed design. The dash-dot-dash broken lines on FIGS. 1 and 8 depict the boundaries of the enlargement that form no part of the claimed design.

1 Claim, 8 Drawing Sheets
